UNITED STATES PATENT OFFICE.

ZACHEUS HALLQUIST, OF OAKLAND, CALIFORNIA.

WASHING MACHINE.

Application filed December 26, 1924. Serial No. 758,076.

This invention relates to a method of washing clothing and an apparatus for carrying out the invention.

It is the principal object of the present invention to provide an improved method and apparatus for washing clothing which employs air under high velocity as a medium for assisting the washing fluid in cleansing the clothing.

10 In carrying out this object, air under high velocity is introduced tangentially into a substantially cylindrical tub containing the clothing and a cleansing medium. The air causes the contents of the tub to very rapidly revolve around the tub and causes considerable agitation of the clothing. It also separates the different articles of clothing so that they will be thoroughly subjected to the action of the cleansing fluid. I have 15 found in actual practice that such agitation is sufficient to thoroughly cleanse clothing in a comparatively short period as the air passes through the clothing loosening the dirt which is removed by the agitation of 20 the clothing and cleansing fluid.

The apparatus for carrying out the method is simple in construction and inexpensive to manufacture in comparison with prior washing machines. Also, by using air a 25 minimum amount of power is required to operate the machine.

I am aware that prior to my invention, water under pressure was employed as agitating means in washing machines by introducing it tangentially into the tub of the machine and causing it to cooperate with a rubbing surface to cleanse the contents of the tub. This method required a circulating pump of large capacity and requiring considerable power. Also, the water could not 30 be practically introduced into the tank at a velocity great enough to cleanse the clothing without the cooperation of a rubbing surface. In eliminating this latter I have reduced the 35 cost of manufacturing the machines. Also by the use of air a more satisfactory washing action is obtained in addition to the fact that less operating power is required and a simpler and less expensive machine provided.

The present invention is exemplified in the following description and the apparatus is illustrated by way of example in the accompanying drawings, in which:

Fig. 1 is an end elevation of the preferred 35 embodiment of my apparatus.

Fig. 2 is a front elevation of the same.

Fig. 3 is a view in rear elevation of the machine.

Referring more particularly to the accompanying drawings, in which I have shown 60 the preferred form of my apparatus, 10 indicates a substantially cylindrical tank having a hinged door 11 into which the cleaning medium and clothes may be introduced into the tank 10.

65 Supported at the top of the tank is an air blower 12 which is operated by an electric motor 14. The discharge port of the air blower is fitted with a nozzle 15 which is outwardly flared at its lower end. This end 70 opens into the tank 10 at the bottom of the latter. The intake opening of the air blower 12 is in communication with the interior of the tank at the top thereof through a connection 16. When the motor 14 is in operation, 75 air under high velocity from the blower is directed into the tank tangentially thereof and causes the contents of the tank to rapidly swirl therein. After circulating around the tank the air is drawn back into 80 the blower through the connection 16. The position of these connections being such that the air, after once passing through the tank, 85 is heated and therefore will not act to cool the contents of the tank upon the second cycle.

In actual practice I have found that by so introducing the air into the tank, it causes the different articles of clothing therein to separate and to be very thoroughly agitated, 90 thereby exposing every portion of the clothing to the action of the cleansing medium in the tank. I have also found that it requires but a minimum power to operate the blower, and that the device is therefore very economical.

95 It is manifest from the drawings and the description that the device is very simple in construction and inexpensive to manufacture when compared with the devices now used for this purpose.

100 While I have shown the preferred form of the invention, it will be understood that various changes in the combination, construction and arrangement of parts may be made, 105 without departing from the spirit of the invention.

Having thus described my invention, what I claim and desire to secure by Letters Patent is:

110 1. A washing machine comprising a horizontally disposed cylindrical tank, an air

blower, a connection between the discharge port of the blower and the interior of the tank, said connection having a flared end opening tangentially into the tank, said air blower being adapted to project a column of air into the tank at a velocity to cause the contents of said tank to rapidly swirl therein and thereby create a washing action.

2. A washing machine comprising a horizontally disposed cylindrical tank, an air

blower, a connection between the discharge port of the blower and the interior of the tank, said connection opening tangentially into the tank, said air blower being adapted to project a column of air into the tank at 15 a velocity to cause the contents of said tank to swirl rapidly therein and thereby create a washing action.

ZACHEUS HALLQUIST.
